(57) **CLAIM**

The ornamental design for a lamp, as shown and described.

DESCRIPTION

This application contains subject matter related to the following co-pending U.S. design patent application:

Application Ser. No. 29/598,018, filed herewith and entitled “LED Holder”.

FIG. 1 is a front and top perspective of a lamp according to the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view taken along line 8-8 of FIG. 2.

The broken lines in the drawings depict unclaimed environmental subject matter.
